UNITED STATES PATENT OFFICE.

JACOB SANDLER, OF BOSTON, MASSACHUSETTS, ASSIGNOR TO SANDLER MFG. CO., OF BOSTON, MASSACHUSETTS, A CORPORATION OF MASSACHUSETTS.

INSTEP-SUPPORT OR ARCH-PROP.

No. 852,625.

Specification of Letters Patent.

Patented May 7, 1907.

Application filed August 15, 1906. Serial No. 330,643.

To all whom it may concern:

Be it known that I, JACOB SANDLER, a citizen of the United States, residing at Boston, in the county of Suffolk and State of Massachusetts, have invented new and useful Improvements in Instep-Supports or Arch-Props, of which the following is a specification.

This invention relates to instep supports or arches which are applied and worn inside of boots or shoes for upholding the arch of the instep to prevent breaking down of the same, or if in any manner impaired, to sustain the parts in normal position and permit them to regain their normal shape and condition.

The object of the present invention is to provide a simple and effective instep support or arch prop of a readily yielding nature to render it comfortable to the wearer and at the same time practical in performing its function without buckling or wrinkling the adjacent leather covering or lining.

With these and other objects in view, the invention consists in the construction and arrangement of the several parts which will be more fully hereinafter described and claimed.

In the drawings, Figure 1 is an inverted plan view of the instep support or arch prop embodying the features of the invention. Fig. 2 is a longitudinal vertical section on the line 2—2, Fig. 1, showing the parts in proper position. Fig. 3 is a transverse vertical section on the line 3—3, Fig. 1, showing the parts in proper position.

Similar numerals indicate corresponding parts throughout the several views.

The numeral 1 designates a thin sheet metal stiffening plate of a resilient nature and preferably formed from steel. Other metals, however, may be used that will retain their shape or the shape desired and also give to the sole piece 2 the necessary arch to support the instep. The plate has an edge contour conforming to that of the boot or shoe adjacent to the instep arch, and is riveted or otherwise fastened to the sole piece 2 as at 3. One side of the plate 1 has an upwardly projecting or laterally curved extension 4 which is so shaped as to conform more

or less closely to the normal arch of a foot at the instep. This up-curved lateral extension is intersected by an outwardly diverging slot 5 extending in a transverse direction and communicating at its inner extremity with a longitudinal relief slot 6. The slot 5 allows for the depression of the plate and particularly the instep of the arch formed by the extension 4. The depression of the entire plate by the weight imposed thereon causes the two edges of the slot 5 to draw nearer to each other and the inner relief slot 6 permits such movement of the edges of the slot 5 toward each other without liability of buckling or fracturing the intermediate part of the plate so that the shape of the entire plate is maintained throughout its extent. The provision of the slots 5 and 6 also obviates breaking down of the plate no matter what weight is disposed thereon. Furthermore, the slots encourage the plate to return to its normal position after a maximum pressure thereon has been relieved. Therefore, the shape of the instep of a boot or shoe is regularly preserved with comfort to the wearer and benefit to the boot or shoe structurally.

It will be seen that the plate is longitudinally arched as well as laterally arched or upturned as just explained and by this double arching of the plate the contour of a boot or shoe is rendered such as to fully conform to the natural shape of a foot.

What I claim is:

An instep support or arch prop comprising a stationary plate of resilient material, a sole piece conforming to an instep arch, means for securing the said stiffening plate to the sole piece, said plate having an upwardly curved projection extending laterally from one side thereof, the said projection having an inwardly tapering slot disposed longitudinally with respect thereto, said projection having a slot communicating with the first-mentioned slot and transverse with respect to the alignment thereof.

In testimony whereof, I affix my signature in presence of two witnesses.

JACOB SANDLER.
